THOMAS S. HOMANS, OF HEMPSTEAD, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,116,279.

Specification of Letters Patent.

Patented Nov. 3, 1914.

Application filed June 18, 1912. Serial No. 704,441.

To all whom it may concern:

Be it known that I, THOMAS S. HOMANS, a citizen of the United States, residing at Hempstead, in the county of Nassau and State of New York, have invented new and useful Improvements in Linotype-Machines, of which the following is a specification.

This invention relates to improvements in linotype machines and more especially to the casting mechanism thereof, and one of the primary objects of the invention is to provide an improved mold disk or wheel the gear teeth of which are offset with respect to the plane of the mold or molds thereon and the longitudinally adjustable liner of each mold may extend beyond the periphery of the disk or wheel without encountering the support or guide which serves to sustain the thrust produced on the mold wheel as the slug is carried past the trimming knife, and without requiring cutting away or otherwise mutilating the disk or wheel to accommodate the liner, the liner and the different parts of the mold being easily accessible for adjustment or manipulation and weakening of the mold disk or wheel is avoided.

Another object of this invention is to provide the mold disk with pads or lugs which are positioned equidistantly in a direction circumferentially of the disk, such pads affording faces which serve to positively and invariably set the mold.

A further object of this invention is to provide an improved longitudinally adjustable liner for varying the length of the mold cavity, the liner according to the present invention being flat and avoids grooving of the body of the mold and thereby limiting the adjustment of the mold.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is a perspective view of a mold disk or wheel constructed in accordance with the preferred embodiment of the present invention; Fig. 2 is a view of the mold wheel showing the same edgewise and partly in section; Fig. 3 shows the mold in elevation, a portion of this figure being in section to illustrate the guiding and positioning key for the improved liner; Fig. 4 is an end elevation of the mold

and its associated parts; Fig. 4^a is a perspective view of a portion of the mold wheel and the coöperating guide or support which sustains the thrust produced upon the mold wheel during the trimming of the slug. 60

Similar parts are designated by the same reference characters in the several views.

In the well known linotype machine as generally constructed, the gear teeth on the periphery of the mold disk overlap the plane 65 of the mold or molds thereon, and in using a liner which is adjustable lengthwise of the mold to vary the length of the mold cavity, a portion of the periphery of the mold wheel, including the web and the gear teeth, is cut 70 away to provide a clearance for the adjustable liner, the cutting away of the mold wheel in this manner being objectionable as it weakens materially the strength of the disk, particularly the gear portion thereof. 75 Moreover, in the linotype machine as generally constructed, the adjustment of the liner is limited for the reason that the liner cannot be projected beyond the periphery of the mold disk, nor enough to encounter the support or guide which coöperates with the circumference of the mold disk and sustains the thrust produced thereon when the slug is carried past the trimming knife. These objections incident to the linotype machine as 80 heretofore constructed are obviated by the present invention, and moreover, the mold disk is considerably stronger, the parts of the mold are readily accessible, and a wide range of adjustment is provided for the liner 85 without interfering with any of the operative parts of the machine, and moreover, simple and effective means is provided for accurately positioning the mold or molds on the disk. 90

The preferred embodiment of the invention is shown in the accompanying drawing and will be hereinafter described in detail, but it is to be understood that the invention is not limited to the particular constructions 100 shown, as different constructions may be used to carry out the principles involved in the present invention.

In the present instance, 1 designates the mold disk or wheel which corresponds in function to that used upon the well known linotype machine, this disk carrying a suitable number of molds and the disk is rotated by a gear which coöperates with the peripheral gear teeth 2 on the disk to set each mold 110

successively in position to cast a slug of type, to trim the foot of the slug, and to eject the slug from the mold. The mold disk embodies a rim 3 and a web 4, the hub 5 of the web coöperating with a supporting shaft 6 which forms an axis about which the disk rotates. A guide or support 7 attached to a suitable part of the machine serves to sustain the thrust produced on the mold disk as the latter carries the cast slug past the trimming knife 8, the latter being supported by a suitable bracket 9 and is shown in dotted lines in Fig. 2. This guide or support 7 has flanges 10 which coöperate with the opposite sides of the peripheral gear teeth 2 of the mold disk and such flanges prevent axial movement of the mold disk with respect to the guide or support.

In order to permit adequate adjustment of the liner which serves to gage the length of the mold cavity without interference between the liner and the guide or support 7 as the mold disk revolves, the peripheral gear teeth of the mold disk, and the mold and its liner occupy different planes in offset relation whereby the liner when projected to or beyond the periphery of the mold disk will clear the guide or support 7, and this offset relation between the mold and liner and the peripheral teeth of the mold disk obviates the necessity of cutting away and thereby mutilating and weakening the peripheral portions of the mold disk. In the present instance, the peripheral gear teeth on the mold disk are offset wholly to one side of the plane of the web 4 while the mold and its related parts are arranged at the opposite side of the web, the mold in the construction shown comprising a mold body 12 the outer portion 13 of which may extend into a recess 14 formed in the web 4 while the inner portion 15 of the mold body lies against the face of the web 4. The surface 16 of the mold body 12 serves as one of the side walls of the mold cavity, and the mold cap 17 which is opposed to the mold body 12 forms the opposite side wall of the mold cavity. The mold cavity is adjusted to cast slugs of different sizes by interposing liners 18 and 19 between the mold body and its cap, and the length of the mold cavity may be adjusted to cast slugs of different lengths by adjusting one of the liners, the liner 18 in the present instance, in a lengthwise direction.

The present invention provides an improved adjustable liner which is flat, that is, it presents plane surfaces at top and bottom, and this adjustable liner is guided longitudinally by a key which is set in the mold body, enabling adjustment of the liner to vary the size of the mold cavity without restriction in the limits of the mold.

In the construction, the longitudinally adjustable liner 18 is provided on its under

side with a longitudinally extending keyway or groove 20 which terminates short of the inner end of the liner, and a key 21 is immovably set or fixed in the mold body 12, the key coöperating with the keyway in the liner and thereby guiding and positioning the same in proper relation to the mold irrespective of the different longitudinal adjustments thereof.

The liners are held in proper position at the opposite ends of the mold by pressure exerted thereon by the mold cap 17 and the mold cap in turn is clamped in position by suitable means, preferably screws, a pair of screws 22 coöperating with the ends of the cap in the present instance and a screw 23 coöperates with the middle or intermediate portion of the mold cap, these screws being tapped for example into the peripheral portion of the mold disk and they operate to retain parts of the mold in operative position. When it is desirable to vary the length of the mold cavity, it is only necessary to loosen the screw 22 which exerts a clamping action on the liner 18, the latter may then be shifted longitudinally of the mold to produce the desired adjustment, and tightening of said screw serves to secure and retain the adjustable liner in the desired adjusted position. By loosening all the screws, the mold cap and both liners may be readily removed.

The matrix-retaining ledge or keeper 24 may be applied to the adjacent face of the mold body 12 as shown, and these two parts may be secured to the mold disk by a suitable number of screws 25.

The present invention provides means for invariably setting or positioning each mold with respect to the mold disk, such means embodying preferably a set of pads or lugs which are located equidistantly in a circumferential direction on the face or web of the mold disk. In the construction shown a set of four pads or lugs 26 is provided, the same projecting from the face of the web 4, and by spacing these pads or lugs equidistantly, a mold may be fitted between any pair of the pads. The drawing shows the mold disk as fitted to receive two molds in diametrically opposite relation, but it is obvious that one or more molds could be added readily. Each pad or lug presents a surface 27 which is adapted to serve as an abutment for one end of the mold body, and by interposing the mold body between two of the pads, the mold obviously is set or positioned invariably in a longitudinal direction on the mold disk. The adjacent surface 28 of each pad or lug may also serve as a gage to position the mold with respect to the center of the mold disk, these surfaces of the pads when finished accurately serving permanently to insure proper location of the mold with respect to the mold disk and the

elements which coöperate with the mold. It is to be observed also that these pads or lugs, being located at the end of the recess 14 which accommodates the mold, serve to reinforce or strengthen the web portion of the mold disk.

What is claimed is:—

1. In a machine of the linotype class, in combination with a mold-carrying wheel, a mold having parts adapted to project to the periphery of said wheel, driving gear teeth on said periphery of the wheel arranged in offset relation to the plane of the mold, and a guide or support for the wheel coöperative with the marginal portions of said gear teeth and adapted to pass between said mold parts and the adjacent margin of the gear teeth.
2. In a linotype machine, a mold disk embodying a web and mold-positioning lugs projecting from one side thereof, a mold secured to said lugs and adapted to cast type high lines, and a rim provided with peripheral gear teeth arranged in a plane at the opposite side of said web and offset with respect to the plane of the mold.
3. In a linotype machine, a mold disk having lugs projecting from one side thereof, a standard mold mounted on the face thereof between and positioned by said lugs for casting type high lines and provided with a longitudinally adjustable liner adapted to project beyond the periphery of the disk, and gear teeth on the disk offset relatively to the plane of the mold and said liner.
4. In a linotype machine, a mold disk having lugs projecting from one side thereof, a standard mold mounted thereon between said lugs for casting type high lines and provided with an adjustable liner adapted to project outwardly beyond the periphery of the disk, gear teeth on the periphery of the disk, said teeth being located wholly to one side of the plane of the mold and said liner, and a mold disk support coöperative with the opposite edges of said gear teeth and arranged to permit clear passage of the outwardly projecting liner.
5. In a linotype machine, a mold-carrying member having outwardly projecting mold-

positioning pads, and a mold located between said pads and having its ends abutting against the same.

55

6. In a linotype machine, the combination of a mold, a mold-carrying member having pads projecting from the face thereof and presenting opposed faces coöperative with the ends of the mold and thereby positioning the same longitudinally.

60

7. In a linotype machine, the combination of a mold, a mold disk having pads projecting therefrom and presenting opposed faces to coöperate with the ends of the mold to position the same longitudinally, said pads also having surfaces coöperative with the mold to position the latter with respect to the center of the disk.

65

8. In a linotype machine, a mold disk having pads projecting therefrom and presenting mold-positioning surfaces, a mold located between and having its ends coöperative with said pads and having a longitudinally adjustable liner adapted to project outwardly beyond the periphery of the disk, driving-gear teeth on the periphery of the disk arranged in offset relation to the plane of the mold and its liner, and a guide or support for the disk coöperative with the marginal portions of said gear teeth and adapted to pass between said liner and the adjacent margin of the gear teeth.

70

9. In a linotype machine, a mold disk having peripheral driving-gear teeth, and provided with mold-positioning pads projecting beyond the plane of the gear teeth, and a mold located between said pads wholly to one side of the plane of the gear teeth and having its ends abutting against said pads.

85

10. In a linotype machine, a mold disk having peripheral driving-gear teeth, and a set of mold-positioning pads projecting laterally beyond the plane of the gear teeth, said pads being spaced equidistantly in a direction circumferentially of the disk.
